UNITED STATES PATENT OFFICE.

CHARLES S. ROGERS, OF KANSAS CITY, MISSOURI, ASSIGNOR OF ONE-THIRD
TO WINFIELD FREEMAN, OF SAME PLACE.

ADJUSTABLE HEAD-REST.

SPECIFICATION forming part of Letters Patent No. 426,069, dated April 22, 1890.

Application filed January 3, 1889. Renewed January 23, 1890. Serial No. 337,799. (No model.)

To all whom it may concern:

Be it known that I, CHARLES S. ROGERS, of Kansas City, Jackson county, Missouri, have invented certain new and useful Improvements in Adjustable Head-Rests, of which the following is a full, clear, and exact description, reference being had to the accompanying drawings, forming a part hereof.

My invention relates particularly to portable head-rests, and has for its object to provide a head-rest that can readily be attached to the back of a car-seat, dentist's, barber, or other chair, and can quickly and easily be adjusted to support the head of the user in many desired positions.

It consists in certain details of construction and arrangement of parts, as will more fully appear in the specification and be pointed out in the claims.

Referring to the drawings, in which similar letters and figures of reference indicate corresponding parts in all the figures, Figure 1 is a perspective view of my improved head-rest adapted to be applied to a barber's chair. Fig. 2 is a side elevation of my head-rest applied to the back of a barber-chair. Fig. 3 is an enlarged view of the clamping device by means of which the rest is securely held in position. Fig. 4 shows details of construction, which will be more fully described farther on. Fig. 5 is a detail view of the clamping device used to secure the head-rest to the back of car-seat. Fig. 6 shows a detail view of knuckle-joint, and Fig. 7 is a section view of same.

In constructing my invention I employ a pad A of any suitable shape, which is pivotally secured at either end between the upright portions of the arm G. Extending downwardly from the middle of the arm G is a standard 3, which terminates in flat circular plate f', said plate being pivoted to a corresponding circular plate B' by means of the screw p, as most clearly shown in Fig. 7. The plate B' is connected to a similar circular plate B by the arm 45 or part d, the plate B being also pivoted to a circular plate f, similar in construction to f', said plate f being formed with a downwardly-projecting cross-piece C, terminating at either end with the curved arms g, adapted to grip 50 the top of the back. Pivoted to the lower

side of the portion C is a clamping-arm D, which has formed on its rear side a screw-threaded lug x, carrying the screw D', which bears against the finger D'' and serves to press the arm D to the back of the chair.

Upon the outer faces of the plates B B', at about their middle portions, are formed the parallel apertured lugs or ears a' a', between which are pivoted the spring-levers a a. At one end of the lever a is pivoted the pin or bolt c, which passes through the aperture e of the plate B or B' and engages with the cone-shaped holes c', formed in the plate f or f'. At the other end of the lever a, upon its underside, is attached the leaf-spring b, which 65 serves to throw the pin c into engagement the moment the pressure is released.

By means of the plates B, B', f, and f', formed and connected as shown, and the spring-levers a a it is clear that the head-rest may be 70 quickly adjusted to any desired angle.

To provide for the further adjustment of the head-rest, I attach the semicircular serrated plate E at one end of the pad A, which works in an opening formed in one of the upright portions of the arm G and is engaged by the cam-shaped turn-pawl F, by which the rest proper can be held at any desired angle.

It is obvious that the straps J J' may be substituted for the clamps C D, and when so 80 desired the arm G, which is cast integral with plate f, is formed with a ratchet-faced projection 2, which engages with a similar projection 1 on the clamp K, said projections 1 2 having the threaded apertures k' k' to receive 85 the binding-screw k. By this arrangement the pad and knuckle-joints can be entirely reversed in case the car-seat is turned over without removing the head-rest from said back, as shown in Fig. 5. Upon the under 90 side of the pad A, I attach a pocket O for the reception of tickets.

The various parts of my invention which are substantial equivalents may be substituted for each other, as desired, without departing 95 from the principles of my invention, and as the manner of operating my device is clear from the above description it needs no further description here.

By the term "knuckle-joint" it will be un- 100

derstood that I refer to each of two engaging plates or disks fB or $f'B'$ and their adjunctive parts.

Having thus described my invention, what I claim is—

1. The adjustable head-rest consisting of the head-support, its supporting frame or bracket, one having a cam-shaped pawl and the other a ratchet, a standard and seat-back clamp or holder, each provided with a circularly-apertured disk or plate and arm d , having a circular plate at each end thereof, and spring-pressed pawls carried thereon and engaging the apertured disks or plates, where-
10 by the standard and seat-back clamp are connected and the head-rest may be adjusted and held in any desired position, substan-
15 tially as described.
2. The adjustable head-rest consisting of

the head-support, its supporting frame or bracket, one having a cam-shaped pawl and the other a ratchet, a standard and seat-back clamp or holder, each provided with a circularly-apertured disk or plate and arm d , having a circular plate at each end thereof, 25 and spring-pressed pawls carried thereon and engaging the apertured disks or plates, said seat-back clamp consisting of a cross-piece having downwardly-projecting arms and a clamping-arm pivoted to said cross-piece and 30 having a screw-threaded lug carrying a screw, substantially as specified.

In testimony whereof I affix my signature in presence of two witnesses.

CHARLES S. ROGERS.
